UNITED STATES PATENT OFFICE

2,342,112

INCENDIARY BOMB

John Bencal, Chicago, Ill.

Application October 18, 1941, Serial No. 415,607

2 Claims. (Cl. 102—65)

The present invention relates to incendiary bombs and has for its main object the provision of a receptacle of frangible material, which on impact with the target may break and shatter to release the inflammable fluid contents, which in turn may be ignited by firing means carried externally by the receptacle.

Another object of the present invention is the utilization of an ordinary glass bottle for a receptacle adapted to be filled with inflammable fluid and which upon impact at the target may spill when the receptacle is broken or shattered and may be ignited by ignition means carried externally by the receptacle.

A still further object of the present invention is the provision of an incendiary bomb of the type hereinabove indicated, and which may be provided with means for facilitating shattering of the receptacle when the same strikes the target and with means for directing the fall of the bomb with the mouth of the bottle disposed downwardly, when a bottle is used, in case the bomb is thrown from an aeroplane, or for directing the mouth of the bottle forwardly when the same is manually thrown and the bomb travels on a horizontal line.

A still further object of the present invention is the provision of an incendiary bomb of the type indicated, and having a bottle filled with inflammable fluid, and which on striking target would shatter and release the inflammable fluid, the latter to be ignited, with means therein provided to direct the travel of the bomb with the mouth of the bottle disposed into the direction of travel.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application, and in which like designating characters refer to corresponding parts throughout the several views:

Fig. 1 is a longitudinal cross-sectional view through the bomb;

Fig. 2 is a transverse cross-sectional view on line 2—2 of Fig. 1;

Fig. 3 is an enlarged transverse cross-sectional view on line 3—3 of Fig. 1;

Fig. 4 is an enlarged transverse cross-sectional view on line 4—4 of Fig. 1; and

Fig. 5 is an enlarged cross-sectional view on line 5—5 of Fig. 1.

Referring to the present drawing in detail there is shown therein a glass bottle 10 having a mouth 11. Bottle 10 is enclosed within canvas casing 12, extending substantially to the neck of the bottle, for the purpose hereinafter stated. Said canvas casing 12 snugly fits the outline of the bottle. Extending from the central body portion of bottle 10 and substantially to the neck portion thereof, is a comparatively thick cover 13 made of cotton or any other suitable absorbent and readily inflammable material. Adjacent both ends of said cover 13, the same is tightly wound by wire strands 14 to maintain said cover 13 in a snug operative position with respect to bottle 10 and canvas casing 12.

5 A pair of clamping members 15 are positioned around the neck of bottle 10 and rigidly maintained thereon by means of a pair of screws 16. Said clamping members 15 carry an ignition casing 17 adapted to receive a supply of inflammable 10 material such as benzine or like inflammable fluid. Said casing 17 carries wick 18 and a flint striking wheel 19, which frictionally contacting with the upper end of flint stone 20 is capable of 15 producing a spark to ignite wick 18 which is saturated with inflammable fluid within casing 17. Said casing 17, wick 18, flint striking wheel 19, and flint stone 20, constitute means for igniting cover 13, as will be hereinafter described, and 20 correspond to the elements found in ordinary cigarette lighters.

Bottle 10 is adapted to receive a supply of 25 inflammable fluid 21, such as gasoline or benzine, which however does not completely fill out bottle 10, but leaves a comparatively small air space as 30 at 22.

When bottle 10 is filled with inflammable fluid 21, it is sealed by stopper 23, which may be made of cork, rubber or any other suitable material, to be receivable within mouth 11 of the bottle. Passing longitudinally of said stopper 23 and in an axial relation therewith is the narrower end of a club-like member 24 which has a plurality of outwardly flaring walls 25 effecting a plurality of 40 angular edges 26. The narrower end of said club-like member 24 terminates in a screw 27 which passes beyond the inner end of stopper 23 and is adapted to receive in a threaded relation, a nut 28 whereby said club-like member 24 may 45 be held in an adjusted rigid relation with said stopper 23.

Said club-like member 24 is comparatively heavy, preferably made of steel or iron casting, so that when the bomb is thrown either manually 50 or from an aeroplane, the same will travel with 55

said club-like member 24 disposed into the direction of the fall, in order that said club-like member 24 may first strike the target. At the impact said member 24 is forced, by its inner end, into the bottle, forcing stopper 23 also into the bottle until edges 26 come in contact with the mouth of the bottle. The air pocket 22 facilitates compression of the contents of bottle 10 and thereby permits shifting of said member 24 into the bottle. Sharp edges 26 cutting into the mouth of the bottle shatter or break the latter so as to spill the contents of the bottle.

Prior to throwing the bomb at the target wick 18 is ignited, which in turn, during the flight of the bomb ignites cover 13 so that the same burns during the flight of the bomb. It is noted that wick 18 in the operative assembly of the bomb is disposed not far from the lower termination of said cover 13. The flame of burning wick 18 will extend to cover 13 when said wick 18 is ignited.

When bottle 10 is shattered by member 24 as hereinabove described, inflammable fluid 21 will spill and will be absorbed by the burning cover 13, as the latter of course will not be fully consumed during the flight of the bomb.

At the impact of member 24 with the target, the force of member 24 driven into bottle 10 will not only break the mouth or neck portions of the bottle but will be capable of shattering the body portion of the bottle. To prevent spilling of fluid 21 beyond the immediate vicinity of cover 13, canvas casing 12 confines fluid 21. Since casing 12 is made of canvas, it will become also saturated with inflammable fluid 21 when the body portion of bottle 10 is shattered and will itself be ignited by the flame of burning cover 13, thus adding to the efficiency of the bomb.

While there is described herein a preferred embodiment of the present invention, it is nevertheless to be understood that minor changes may be made therein without departing from the spirit and scope of the invention as claimed.

What I claim as new is:

1. An incendiary bomb comprising a receptacle of frangible material, a quantity of inflammable material therewithin, a casing of fibrous material enveloping said receptacle, a wadding cover enveloping said casing, said receptacle being adapted to be shattered on striking a target for releasing said inflammable material, the released inflammable material being adapted to saturate 15 said wadding cover and said casing and to be substantially retained within the confines of the latter, and means carried by said receptacle for igniting said wadding cover prior to the release of said inflammable material and said casing 20 when the same is saturated by the released inflammable material from said receptacle when the latter is shattered.

2. An incendiary bomb comprising a flask of frangible material, said flask including a constricted end defining a mouth, a quantity of inflammable material within said flask, a stopper receivable within said mouth for normally sealing said flask, a weight carried by said stopper, said weight being of an oblong formation and of substantially polygonal shape on cross-section, said weight being adapted to be driven into the mouth of the flask and by its edges to cut thereinto for the purpose of shattering the flask when said weight contacts with the target, and means for 35 igniting said inflammable material when said flask is shattered on hitting the target.

JOHN BENCAL.
